UNITED STATES PATENT OFFICE.

ROY B. SHANCK, OF KINGSTON, NEW YORK, ASSIGNOR TO AMERICAN TELEPHONE AND TELEGRAPH COMPANY, A CORPORATION OF NEW YORK.

COMPOSITE RINGER.

1,366,423.

Specification of Letters Patent.

Patented Jan. 25, 1921.

Application filed May 21, 1919. Serial No. 298,654.

To all whom it may concern:

Be it known that I, Roy B. SHANCK, residing at Kingston, in the county of Ulster and State of New York, have invented certain Improvements in Composite Ringers, of which the following is a specification.

This invention relates to transmission lines which are composed for telephone and telegraph service and more particularly to the signaling or ringing arrangements associated therewith.

It has often been found desirable to associate with a transmission line composed for both telephone and telegraph service, arrangements for relaying ringing current transmitted over the line and such arrangements are particularly desirable for relaying ringing current about repeater elements included in a line. It has been found in practice that with former relaying arrangements, the relayed ringing current would have a tendency to leak back over the telegraph conductors which connect the two sections of the composited line independently of the relaying arrangements and cause the relaying arrangements to become locked in a working position, thereby causing a steady ring over the transmission line. Accordingly, it is one of the objects of this invention to provide means for relaying ringing current from one section of a transmission line to another section of the same line or other lines, and in associating with such relaying means arrangements which will insure the restoration to normal of the relaying means upon the cessation of the original ringing current coming in over the line. A further object consists in providing means for preventing the occurrence of false ringing over a transmission line connected telegraphically with sections of other lines when ringing current is being transmitted over such sections. Other and further objects of the invention will be clear from the detailed description of the operation to be given later.

In the arrangement of this invention, relay means responsive to ringing current transmitted over the line are bridged across the midpoints of windings of the usual transformer associated with the repeater output circuits. The operation of either of these ringing responsive relays will operate means on the other side of the repeater apparatus whereby ringing current will be applied

equally to the conductors associated with the outgoing section of the transmission line and to the conductors associated with the network adapted to balance said line section. The two networks which balance the 60 respective sections of the transmission line are interconnected by conductors having an impedance equal to the telegraph conductors which interconnect the two line sections. By the above arrangements, any of the relayed 65 ringing current which leaks back over the telegraph conductors to the incoming line and the conductors connected thereto will be opposed by an equal and opposite current which leaks back over the conductors inter- 70 connecting the networks and which tends to produce a potential equal and opposite thereto. These currents will accordingly neutralize each other and have no effect on the relay arrangements.

The invention may be more fully understood with reference to the accompanying drawings, in the Figure 1 of which is illustrated a preferred form of the circuit arrangements of the invention; in the Fig. 2 of which is illustrated a modification thereof. Similar reference numerals have been used to denote like parts in both figures. For purposes of convenience, the relaying arrangements have been illustrated as associated with a cord circuit including the repeater elements 16 and 23 and adapted for interconnecting the lines L_1 , L_2 , L_3 and L_4 , although it will be understood that the arrangements of the invention might equally 85 well be associated with a two-way two-element repeater directly connected to the lines or with other means for connecting the lines telephonically. The repeater elements 16 and 23 are shown as of the mechanical type, 90 although other types, such as the vacuum tube repeater, may be employed. Associated with the lines L_1 , L_2 , L_3 and L_4 are the artificial lines or networks N_1 , N_2 , N_3 and N_4 adapted to balance the lines respectively. 95 The lines L_2 and L_3 are interconnected for telegraph purposes by the conductors 1 and 2 in which are included the inductances 5 and 6 which offer a high impedance to telephone currents but do not interfere with the 100 transmission of telegraph currents. The networks N_2 and N_3 are interconnected by conductors 3 and 4 in which are included the inductances 7 and 8 which are similar to inductances 5 and 6. Included in the lines L_2 110

and L_3 are condensers, such as 9 and 10, which prevent telegraph currents from being transmitted to the telephone apparatus connecting the lines but which do not hinder the transmission of telephone currents thereto. Bridged across the lines L_2 and L_3 are the inductances 11 and 12, respectively, each having a tap to ground. These inductances are of high impedance to telephone currents but are of low impedance to telegraph currents and accordingly serve to shunt to ground any telegraph currents which may pass through the condensers such as condensers 9 or 10.

In Fig. 1 the output circuits of the repeaters 23 and 16 are shown associated with the usual type of three-winding transformers which include the windings 12, 13 and 14 and the windings 19, 20 and 21 respectively. Bridged across the midpoints of windings 12 and 13 is the relay 15 which is responsive to ringing currents coming in over a section of the line. Controlled by relay 15 are the relays 28 and 29 upon the operation of which ringing current from the source 25 will be applied equally to the conductors leading to the outgoing section of the transmission line and to the network adapted for balancing said line section. Bridged across the midpoints of windings 19 and 20 is the relay 22 which is responsive to ringing currents coming in over a section of the line. Controlled by relay 22 are the relays 26 and 27 which serve to apply ringing current from the source 18 equally to the conductors leading to an outgoing section of the transmission line and to the conductors leading to the network adapted for balancing said line section.

The operation of the arrangements illustrated in Fig. 1 is as follows: If the lines L_2 and L_3 are interconnected by the cord circuit by inserting the plugs P_1 and P_2 into the jacks J_2 and J_3 , respectively, ringing current coming in over the line L_2 will be transmitted over the following circuit: from the tip conductor of line L_2 , tip contacts of jack J_2 and plug P_1 , conductor 30, armature and contact of relay 26, conductor 31, upper portion of winding 13, from the midpoints of winding 13 through the winding of relay 15 and thence to the midpoints of winding 12; thence through the upper portion of winding 12, conductor 32, contact and armature of relay 26, conductor 33, ring contacts of plug P_1 and jack J_2 to the ring conductor of line L_2 . As the winding of relay 15 is included in the above mentioned ringing circuit, the relay 15 will be energized and will pull up its armature and close the following circuit: from ground, armature and contact of relay 15, conductor 34, winding of relay 28, conductor 35, winding of relay 29 to battery and ground. The closing of this circuit will operate the relays 28 and 29. Upon the operation of relays 28 and 29 the source 25 of ring-

ing current will be connected over conductors 40 and 41 to conductors 37 and 39, respectively. At the same time ground will be applied to conductors 36 and 38. Accordingly ringing current from the source 25 will now be transmitted out over the line L_3 as follows: from source 25 over conductor 41, contact and armature of relay 29, conductor 39, lower ring contacts of plug P_2 and jack J_3 , out over the ring conductor of line L_3 and back over the tip conductor of line L_3 , lower tip contacts of jack J_3 and plug P_2 , conductor 38, armature and contact of relay 29 to ground. At the same time an equal ringing current from the source 25 will be transmitted through the network N_3 as follows: from source 25, over conductor 40, contact and armature of relay 28, conductor 37, upper ring contacts of plug P_2 and jack J_3 , through the network N_3 and back to the upper tip contacts of jack J_3 and plug P_2 , over conductor 36, armature and contact of relay 28, to ground. The portion of the ringing current from source 25 which was transmitted as described out over the line L_3 may have a tendency to leak back over the telegraph conductors 1 and 2 to the line L_2 and thence to the ringing responsive relay 15 as follows: from the ring conductor of line L_3 , over telegraph conductor 1, over tip conductor of line L_2 , upper tip contacts of jack J_2 and plug P_1 , over conductor 30, contact and armature of relay 26, conductor 31, winding 13, from midpoint of winding 13, through the winding of relay 15 to the midpoint of winding 12; from winding 12, over conductor 32, contact and armature of relay 26, conductor 33, upper ring contacts of plug P_1 and jack J_2 , ring conductor of line L_2 and over telegraph conductor 2 to the tip conductor of line L_3 . However at the same time the other portion of the ringing current from source 25 which was transmitted through the network N_3 would have a tendency to leak back over telegraph conductors 3 and 4 to the ringing responsive relay 15 in the following manner: From the ring conductor associated with network N_3 , over conductor 3, tip conductor associated with network N_2 , lower tip contacts of jack J_2 and plug P_1 , conductor 42, armature and contact of relay 27, conductor 43 to the midpoint of winding 12; from the midpoint of winding 12, through the winding of relay 15 to the midpoint of winding 13; from the midpoint of winding 13, over conductor 44, contact and armature of relay 27, conductor 45, lower ring contacts of plug P_1 and jack J_2 and over conductor 4 to the tip conductor associated with network N_3 . It will be seen that the direction of this last mentioned current which has a tendency to leak back to the ringing relay 15, over the telegraph conductors 3 and 4, is directly opposite to the direction of the current which has a tendency to leak

back to the ringing responsive relay 15 over the telegraph conductors 1 and 2, the current leaking back over conductors 1 and 2 being transmitted from the midpoint of 5 winding 13, through the winding of relay 15, to the midpoint of winding 12, and the current leaking back over conductors 3 and 4 being transmitted from the midpoint of winding 12, through the winding of relay 15 10 to the midpoint of winding 13. As these two currents originate from a common source 25 and are equal, and tend to flow through the windings of relay 15 in opposite directions, and as each of these currents would be 15 equally attenuated by the inductances 5, 6, 7 and 8, it will be seen that these currents will neutralize each other and accordingly will cause no interference with the ringing responsive relay 15. 20 In like manner, ringing current coming in over the line L_3 will operate the ringing responsive relay 22 which in turn controls the relays 26 and 27, whereby ringing current from the source 18 may be applied 25 equally to conductors 30 and 33 associated with line L_2 and to conductors 42 and 45 associated with the network N_2 .

A portion of the ringing current thus transmitted in relay form out over the line 30 L_2 may leak back over the telegraph conductors 1 and 2 to the line L_3 and thence to the ringing responsive relay 22. However, this current would be neutralized by an equal current which would tend to leak back 35 over the conductors 3 and 4 and would tend to flow through the ringing responsive relay 22 in an opposite direction and accordingly would cause no interference with the ringing responsive relay 22. As the operation 40 would be substantially similar to that previously described with respect to ringing current coming in over the line L_2 , no further description thereof will be given.

If a connection should be made between 45 the lines L_1 and L_2 and at the same time a connection be made between the lines L_2 and L_4 , with cord circuits or arrangements employing former types of relaying means for ringing current, it will be seen that the 50 relayed ringing current transmitted out over the line L_3 might leak back over the telegraph conductors 1 and 2 to the line L_2 and actuate the ringing means interconnecting the lines L_2 and L_4 , and accordingly 55 cause a false ring to result over line L_4 . However if the lines L_1 and L_3 and the lines L_2 and L_4 are interconnected by cord circuits employing the relay means of this 60 invention, the possibility of relayed ringing current leaking back from line L_3 to line L_2 over conductors 1 and 2 and operating the relaying means in the cord circuit interconnecting lines L_2 and L_4 will be obviated, as such ringing current would be neutralized 65 in the cord circuit interconnecting lines L_2

and L_4 by an equal current leaking back over conductors 3 and 4 and tending to flow through the relaying means in an opposite direction. As the description of this operation would be substantially the same as 70 has been previously given, a further description of the circuits will be omitted.

In the arrangements illustrated in Fig. 2 the ringing responsive relays 15 and 22 control the relays 24 and 17 respectively. The 75 relays 17 and 24 disconnect the output circuits of the repeaters from the usual transformers and connect the source of ringing current to such transformers in a manner similar to the currents used for the transmission of speech. The currents which tend to leak back over the telegraph conductors 80 will neutralize each other in the same manner as previously pointed out with respect to Fig. 1. Accordingly no further description 85 of the arrangements of Fig. 2 will be given.

While the invention has been disclosed in certain specific arrangements which have been deemed desirable, it is understood that 90 it is not specifically limited to cord circuits as illustrated, but may be employed with repeater apparatus permanently associated with the transmission line or with other means for connecting lines telephonically, 95 and may be embodied in many and other widely varied forms without departing from the spirit of the invention, as defined in the appended claims.

What I claim is:

100

1. A composite signaling system comprising a pair of transmission lines, means to connect said lines for telephone purposes, means to connect said lines for telegraph purposes, a source of ringing current, means responsive to ringing current transmitted over one of said lines to apply said source to the other line, whereby ringing current is transmitted over said line and over said 105 means to connect said lines for telegraph purposes, and means to prevent the current transmitted over the latter path from affecting said responsive means.

2. In a telephone system, two line sections, repeaters for connecting said line 115 sections, ringing relays associated with said line sections, telegraph conductors bridged around said repeaters, means responsive to ringing current coming in over one of said line sections for applying ringing current 120 to the other line section and over said telegraph conductors to the first mentioned line section, thereby producing a potential difference tending to cause a current to flow in one direction through the winding of the 125 ringing relay associated with said first mentioned line section, and means for simultaneously producing a potential difference tending to cause a current to flow in the opposite direction through said winding.

130

3. A plurality of transmission lines, networks for balancing said lines, telegraph conductors connecting two of said lines and telegraph conductors connecting two of said networks, means to connect one of said last mentioned lines with a third line for telephone purposes, means associated with said connecting arrangements and responsive to current coming in over one of said lines interconnected for telephone purposes for applying ringing current to the other of the interconnected lines, whereby ringing current is transmitted over said telegraph conductors to the second of said first mentioned two lines, means to connect said last mentioned line with another line for telephone purposes, means associated with said last mentioned connecting arrangements and responsive to current coming in over one of said last mentioned interconnected lines for applying ringing current to the other of

said last mentioned interconnected lines, and means to prevent the ringing current applied to the lines by said first mentioned connecting arrangements from affecting the responsive means associated with said second mentioned connecting arrangements. 25

4. A telephone repeater system comprising two line sections, repeaters connecting said line sections, a normally disconnected source of ringing current associated with the output circuit of one of said repeaters, and means responsive to ringing current received over one of said line sections to disconnect said repeater from said output circuit and to connect said source to said output circuit. 30 35

In testimony whereof, I have signed my name to this specification this 19th day of May 1919.

ROY B. SHANCK.
